UNITED STATES PATENT OFFICE

92,170

DESIGN FOR A BATTER PITCHER

Ralph T. Ganary, Westmont, N. J.

Application February 10, 1934, Serial No. 50,684

Term of patent 14 years

To all whom it may concern:

Be it known that I, RALPH T. GANARY, a citizen of the United States, residing at Westmont, in the county of Camden and State of New Jersey, have invented a new, original, and ornamental Design for a Batter Pitcher, of which the following is a specification, reference being had to the accompanying drawing, forming part thereof.

In the drawing:

Fig. 1 is a front elevation of the article showing my new design.

Fig. 2 is a top plan view.

Fig. 3 is a bottom plan view.

The essential feature of my design consists of the general outline of the container which comprises a plurality of parallel cylinders, the bottom centers of which are perforated, which perforations form the apexes of a geometrical figure or polygon and surmounted by a handle, harmonizing in arrangement and proportions with the cylinders.

I claim:

The ornamental design for a batter pitcher as shown and described.

RALPH T. GANARY.
